T. C. POMEROY

HYDRAULIC APPARATUS

Filed Nov. 8, 1924

UNITED STATES PATENT OFFICE.

TIMOTHY CYRIL POMEROY, OF MOLINE, ILLINOIS, ASSIGNOR OF ONE-THIRD TO
JEREMIAH E. MADDEN, OF CHICAGO, ILLINOIS.

HYDRAULIC APPARATUS.

Application filed November 8, 1924. Serial No. 748,677.

This invention relates to new and useful improvements in hydraulic apparatus such as hydraulic jacks, pumps, rams, etc. employing a liquid medium to transmit power, and more particularly relates to hydraulic lifting jacks such as are commonly employed for lifting the wheels and axles of automobiles, trucks, etc.

An object of the invention is to provide means operable in conjunction with such devices whereby the operating liquid contained therein, will automatically be returned to its source when the movable member therein reaches the limit of its effective stroke, thereby preventing the apparatus from being subjected to unnecessary strains as a result of excessive internal pressure caused by continued pumping or forcing of the liquid against the movable member after having reached said limit.

A further and more specific object of the invention is to provide a hydraulic device having a plunger operatively mounted therein which is provided with a valve mechanism adapted to be actuated when the plunger reaches the limit of its effective or work stroke, thereby allowing a portion of the liquid to escape from beneath the plunger and thus eliminate any danger of an excessive pressure being built up within the device, which might result in serious damage thereto.

A further object of the invention is to provide a liquid release valve-mechanism of simple and inexpensive construction which is particularly adaptable for use in conjunction with such hydraulic devices as the lifting jack shown and described in the prior pending joint application of the inventor hereof and Carl E. Johnson, filed August 28, 1924, Serial No. 734,730.

The particular object of the invention therefore is to provide a simple and improved means operable in conjunction with a hydraulic device to render such device efficient and fool-proof in operation.

Other objects of the invention will appear from the following description and the accompanying drawings and will be pointed out in the annexed claims.

In the drawings, there has been disclosed a structure designed to carry out the various objects of the invention but it is to be understood that the invention is not confined to the exact features shown, as various changes may

be made within the scope of the claims which follow.

In the drawings:

Figure 1 is a view in sectional elevation of a hydraulic jack showing my invention applied thereto;

Figure 2 is a sectional view on the line 2-2 of Figure 1 showing the means for actuating the valve mechanism;

Figure 3 is a cross-sectional view on the line 3-3 of Figure 2; and

Figure 4 shows a valve-mechanism of modified construction.

In the selected embodiment of the invention here shown there is illustrated, for purposes of disclosure, a form of jack such as the one shown in the above mentioned prior pending application, Serial No. 734,730. This jack comprises a cylinder 4 mounted in a suitable base 5 and having a piston rod 6 slidably mounted therein. The lower end of the piston rod 6 has a plate 7 secured thereto and a leather cup or packing 8 is mounted on the lower face of this plate as shown in Figure 1. A lifting head 9 is mounted on the upper end of the piston rod and a discharge tube 11 and an intake tube 12 are mounted within the piston rod and have their upper ends secured to the lifting head 9 by such means as the threads 13. The lower ends of the tubes 11 and 12 pass through apertures provided in the plate 7 and packing 8, and also through a relatively smaller plate or washer 14. The lower ends of the tubes are threaded to receive the nuts 15 and 16 by means of which the lifting head, piston rod, plate 7, packing 8 and washer 9 may be securely tied together for operation as a unit. It will be noted that the nut 15 is open at the bottom so that the lower portion of the cylinder 4 will be in communication with the lifting head 9 through the discharge tube 11, and that the nut 16 on the lower end of the intake tube provides a closure for the end of said tube.

A passage 17 is provided in the lifting head 9 and upwardly extends from the upper end of the intake pipe to a horizontal duct 18 provided in the lifting head. A similar passage 19 connects the upper end of the discharge tube 11 with the horizontal duct 18. Suitable check valves 21 and 22 are provided in the horizontal duct 18 and the passage 17, respectively, as shown in the upper portion of Figure 1. These valves function to pre-

vent the operating fluid contained within the jack, from returning to the interior of the piston rod when the jack is being operated to lift a load.

- 5 The means provided for pumping the fluid from the interior of the piston rod to beneath the piston head resides in the provision of a displacement pump mounted within a section 10 of the jack handle which preferably is made in two sections as shown. The intermediate handle section 23 is pivotally secured to the lifting head by means of a tapered plug valve 24, the construction of which is clearly shown in the above-mentioned prior pending application and it is therefore not necessary that this pivotal joint be here shown in detail. The outer or pump section 25 of the handle is similarly connected to the intermediate handle section 23 by means of a tapered valve 20 plug 26 similar in construction to the pivot 24 connecting the intermediate handle section to the lifting head of the jack. A pump rod 27 is reciprocally mounted within the handle section 25 and has an operating handle 28 secured to the upper end thereby whereby it may be manually actuated when it is desired to raise the lifting head of the jack. A suitable packing box 29 is provided in the handle section 25 to prevent the leakage of oil from the handle when the pump rod is being actuated.

In the operation of the form of jack here shown fluid is drawn from the interior of the piston rod through a port 31 provided in 35 the wall of the intake tube 12 adjacent the lower end thereof, thence upwardly through the tube through the vertical passage 17, by the check valve 22, through the horizontal duct 18, and into the tapered plug 24 connecting the handle to the lifting head. From the tapered plug it is drawn through an aperture 32 provided in the plug and into the relatively larger intermediate handle section 23, thence through the joint 26 and into the 40 pump section 25 of the handle, substantially following the pump rod 27 as it is upwardly drawn in the pump section 25 of the handle. The pump rod 27 is then downwardly forced against the fluid with the result that such 45 fluid will be forced out of the handle and back through the tapered plug 24, through the horizontal duct 18, by the check valve 21, and into the passage 19, thence downwardly through the discharge tube 11 and 50 into the bottom of the cylinder beneath the piston head. Such pumping of the liquid from within the piston rod to a point beneath the piston head will cause the latter to gradually ascend. It is to be understood that during 55 the operation of the pump the check valves 21 and 22 will alternately close and open as the fluid is drawn from the piston rod and pumped into the lower portion of the cylinder. Suitable means are provided in 60 jacks of this type to permit the return of the

oil from the cylinder back to the piston but as this part of the jack forms no part of the present invention, I have thought it unnecessary to show same in detail, it being understood that such means are provided.

An important feature of this invention resides in the novel means provided for preventing excessive pressure from being built up in the jack when the lifting head has reached the uppermost limit of its movement, should the operator continue to actuate the pump. Such means preferably consists in the provision of a valve mechanism mounted in the piston head which is actuatable when the piston reaches the limit of its upward movement to release a portion of the liquid pumped beneath the piston head.

As shown in Figure 2, a flanged sleeve 33 is mounted in the piston head and has its upper end in threaded engagement with the plate 7. A suitable packing washer 34 is preferably interposed between the flanged head 35 of the sleeve and the washer 14 in order that a tight joint may be provided therebetween to prevent the leakage of oil therethrough. A conical valve seat 36 is formed in the lower end of the sleeve 33 and has a ball check valve 37 yieldably seated therein by means of a tension spring 38 having its other end secured to a stud 39 by a screw 41 (Figure 3). The stud 39 is similarly secured to the plate 7 by having its upper end in threaded engagement therewith, as shown. A packing 34 is likewise provided under the head of the stud 39 to prevent leakage through the piston head. The spring 38 functions normally to retain the ball 37 in closed inoperative position.

The means provided for actuating the valve 37 when the piston rod reaches the limit of its upward movement consists of a rod 42 which is transversely mounted within the piston rod and has its ends outwardly projecting through the wall thereof through elongated openings 43. A relatively smaller rod 44 is interposed between the transverse rod 42 and the ball check valve 37 so that when the rod 42 is downwardly moved within the piston rod the valve will be downwardly moved to open position against the tension of the spring 38.

Referring to the drawings, it will be noted that the upper major portion of the piston rod is of a relatively smaller diameter than the lower portion thereof, thereby forming on the piston rod an annular shoulder 45 which is slightly above the axis of the transverse rod 42 when the latter is in normal position as shown in Figures 1 and 2. This annular shoulder 45 is adapted to engage an annular ring or detent 46 mounted at the upper end of the cylinder in abutting relation thereto. A packing 47 is mounted above the detent 46 and is compressed against the walls of the piston rod by means of a packing

nut 48 which is in threaded engagement with the upper end of the cylinder 4.

In the operation of a jack or other hydraulically-operated device employing this novel fluid releasing valve mechanism, the piston or movable member therein will be raised by pumping or forcing the fluid under the movable member as hereinbefore described. As soon as the piston or movable member reaches the uppermost limit of its lifting or work stroke, the ends of the transverse rod 42 will engage the detent ring 46 thereby downwardly forcing the rod 44 against the ball check valve 37 with the result that the valve will be opened to allow a portion of the fluid being pumped under the piston head to escape through the valve and back to the interior of the piston rod. Thus it will readily be seen that by the employment of this novel fluid releasing mechanism, it will be impossible for an inexperienced operator or novice to injure or damage the jack or other hydraulic device with which it is used by the continued pumping or forcing of fluid under the movable member, as a result of the fluid being permitted to escape through the valve sleeve 33 and back to the interior of the piston rod or its source. As soon as the operator ceases to actuate the pump rod 27, the spring 28 will immediately cause the valve 37 to be closed so that the piston rod will remain in load-lifting position and will thus remain until the mechanism provided for returning the fluid from beneath the piston has been actuated by manipulation of the handle or other means, not shown.

This novel device is of further value in that it will prevent the pumping means from becoming inoperative by losing its prime which might be caused by the leakage of fluid from the apparatus when compressed to an excessively high pressure. Therefore, by thus preventing excessive pressures from being built up within the apparatus, such apparatus will be rendered substantially fool-proof.

In Figure 4, there is shown a modified construction employing a hollow stud 49 having a conical valve seat 51 provided at its upper end against which a ball valve 52 is seated by means of a compression spring 53 interposed between the ball 52 and a cap 54 secured to the lower end of the stud 49. A valve-actuating rod 55 has one end in engagement with the ball 52 and upwardly extends therefrom at an incline through an elongated opening 56 provided in the lower enlarged portion of the piston rod. The upper end of the inclined rod 55 extends to a point slightly above the annular shoulder 45 of the piston rod so that when the piston rod is upwardly moved within the cylinder the end of the valve actuating rod will engage the annular detent ring 46 at the upper end of the cylinder and thereby cause the

valve 52 to be opened. Such opening of the valve 52 will permit the fluid pumped beneath the piston head to escape through an aperture 57 provided in the cap 54 and upwardly through the hollow stud 49 and by the open valve 52 and thence into the hollow piston rod thereby causing the pressure beneath the piston head to be lessened.

Having thus described my invention what I claim as new and desire to secure by Letters-Patent, is:

1. In a hydraulic device, the combination of a stationary cylinder, a hollow plunger mounted to reciprocate within the cylinder and provided at one end with a piston head, a fluid transferable to the cylinder from the interior of the plunger, a valve-controlled conduit within the plunger for withdrawal of fluid therefrom and having its intake positioned adjacent to the piston head, a valve-controlled conduit for delivering fluid to the cylinder beneath the piston head, a pump operatively connected with both of said conduits for discharge of fluid from the plunger through one conduit and delivering it to the cylinder beneath the piston head through the other conduit, a normally closed valve in the piston head, and operating means for said valve positioned above the intake of said first mentioned conduit and adapted to be engaged by stationary means to open said valve to prevent the withdrawal of all the fluid from the plunger and loss of prime in the pump.

2. In a hydraulic device, the combination of a stationary cylinder, a hollow plunger mounted to reciprocate within the cylinder and provided at one end with a lifting member and at its other end with a piston head, a fluid transferable to the cylinder from the interior of the plunger, a valve-controlled conduit for discharge of fluid from the plunger and having its intake positioned adjacent to the piston head, a valve-controlled conduit for delivering fluid to the cylinder beneath the piston head, a pump operatively connected with both of said conduits for discharge of fluid from the plunger through one conduit and delivering it to the cylinder beneath the piston head through the other conduit, a normally closed spring-actuated valve in the piston head of the hollow plunger, and a valve-actuating member operatively connected with said valve and positioned above the intake to said first mentioned conduit and protruding through the wall of said hollow plunger and adapted to be engaged by stationary means to open said valve to prevent withdrawal of all the fluid from the plunger to prevent loss of prime in the pump.

3. In a hydraulic device, the combination of a stationary cylinder, a hollow piston member mounted to reciprocate within the cylinder and provided with a lifting head, a fluid transferable to the cylinder from the interior

of the piston, a valve controlled discharge conduit from the hollow piston, a valve controlled conduit for delivering fluid to the cylinder beneath the piston head, both of said conduits being positioned within the hollow piston and communicable one with the other through the piston lifting head, the discharge conduit having an intake port positioned adjacent to the piston head for passage of fluid from the hollow piston into said conduit, a pump operatively connected with both of said conduits for withdrawal of fluid from the hollow piston through one conduit and delivering it to the cylinder beneath the

16 piston head through the other conduit, and a normally closed valve in the piston head operable at a predetermined point in the travel of the piston to open communication for flow of fluid between the cylinder and the hollow piston through the piston head and 20 maintain sufficient fluid in the hollow piston between the intake of the discharge conduit and adjacent face of the piston head to insure a prime for the pump throughout the lifting stroke of the piston.

25 In witness whereof, I have hereunto set my hand this 3rd day of November, 1924.

TIMOTHY CYRIL POMEROY.
